UNITED STATES PATENT OFFICE.

ABRAHAM AARONS, OF NEW YORK, N. Y.

DESIGN FOR A LIGHTING FIXTURE.

Application filed March 18, 1924. Serial No. 8,980. Term of patent 3½ years.

To all whom it may concern:

Be it known that I, ABRAHAM AARONS, a citizen of the United States of America, and a resident of the borough of the Bronx, Bronx County, city and State of New York, have invented a new, original, and ornamental Design for a Lighting Fixture, of which the following description, in connection with the accompanying drawing, is a specification.

Figure 1 of the drawing is a bottom plan view; and

Figure 2 of the drawing is a side elevation of the lighting fixture showing my new design.

I claim as my invention:

The ornamental design for a lighting fixture, as shown.

ABRAHAM AARONS.
